(57) **CLAIM**

The ornamental design for a chair, as shown and described.

DESCRIPTION

FIG. 1 is a rear perspective view of a chair according to a fourth embodiment.

FIG. 2 is a front perspective view of the chair of FIG. 1. FIG. 3 is a left-side perspective view of the chair of FIG. 1; and,

FIG. 4 is a left-side view of the chair of FIG. 1. The right-side view being the same as the left-side view. The dash-dash broken lines in the figures and the areas within the dash-dash broken lines show portions of the chair that form no part of the claimed design.

1 Claim, 4 Drawing Sheets
